(57) **CLAIM**

The ornamental design for an orthopedic device, as shown and described.

DESCRIPTION

FIG. 1 is a perspective view of an orthopedic device, showing my new design;

FIG. 2 is a front elevational view according to the device of FIG. 1.

FIG. 3 is a first side elevational view according to the device of FIG. 1.

FIG. 4 is a rear elevational view according to the device of FIG. 1.

FIG. 5 is a second side elevational view according to the device of FIG. 1; and,

FIG. 6 is a top plan view according to the device of FIG. 1.

The broken lines immediately adjacent to the claimed surfaces define the bounds of the claimed design. All other broken lines represent environmental structure. None of the broken lines form part of the claimed design.
